GAME COMBINING JIGSAW PUZZLE
AND QUIZ

Milton C. Grace, New Orleans, La.

Application October 29, 1946; Serial No. 706,462

4 Claims. (Cl. 35—9)

1

This invention relates to a game of that type which calls for cooperative, rather than competitive skill, in the playing. It is based on a jigsaw puzzle in which the position of the pieces is determined through the instrumentality of a "quiz," thus adding to the educational value of the game.

One of the objects of the invention is to provide a game employing coordinated elements including a game board, a set of jigsaw puzzle pieces and a key card, the face of the game board having indicated areas where specific jigsaw pieces belong, the key card containing a plurality of printed questions, answers, pictures, or the like, together with a clue in the form of an index for each item, different for each item and corresponding to the indicia on the game board. The jigsaw pieces each have an inscription complementary to the respective inscriptions on the key card, but no clue directly relating them to the indicia on the game board, so that the players must use the intellectual step of associating the inscription on the piece with the complementary inscription on the key card, in order to discover the clue which matches the locating index on the game board.

Other objects of the invention will appear as the following description of a preferred and practical embodiment thereof proceeds.

In the drawing which accompanies and forms a part of the following specification, and throughout the figures of which the same reference characters have been used to denote identical parts:

Figure 1 is a plan view of the game board;

Figure 2 is a plan view of a jigsaw piece;

Figures 3 and 4 are plan views of quiz cards;

Figure 5 is a fragmentary plan view of a portion of the game board, showing several adjacent jigsaw pieces in position;

Figure 6 is a similar view showing a variant in which the jigsaw puzzle in the aggregate is covered by a picture overprint.

Referring now in detail to the several figures, the numeral 1 represents a game board, preferably made of stiff material having a planiform surface, and having printed thereon in distributive relation a pattern of indicia 2, which in the examples shown, is a series of consecutive numbers arranged in rows, but which may be letters, words, pictures, or other characters. The board 1 functions as a support for a jigsaw puzzle, and the indicia 2 indicate, but do not delineate, areas upon which specific jigsaw pieces belong. In Figure 2, which shows a representative one 3 of the jigsaw pieces, it is seen that they do not bear any index which directly relates them to the indicia inscribed on the game board.

2

Figures 3 and 4 show key cards 4 and 5, respectively, several of which are preferably employed. These preferably refer to different subjects, each bearing a series of printed informative items, the aggregate number on all key cards being not less than the number of jigsaw pieces. In the examples shown, one card lists items under the head of "Sports," and the other, items under the head of "History." The items are in the form of a series of quiz questions, and each is associated with an adjacently printed index 6, said indexes corresponding to indicia 2 on the game board 1.

The jigsaw pieces 3 each has an inscription printed thereupon which complements an item 6 on the key cards. Thus the word "Jackson" on the jigsaw piece 3 in Figure 2 coordinates with the phrase "Old Hickory" on the "History" key card, and "Old Hickory" has the adjacent index 51 on the key card, which relates to the corresponding index 51 on the game board, so that by this chain of associations, the proper area is located on the game board for the placing of that particular jigsaw piece 3. The indicia 2 on the game board are preferably placed approximately at the centers of the areas which they designate, and the jigsaw pieces 3 are preferably provided with a centrally located marker 9, which serves as a guide in centering the jigsaw piece with respect to the area of the game board in which it is placed.

From the above description it will be understood that the player must perform an intellectual step in correlating the inscription on the jigsaw piece with the complementary item on the key card, before he is able to discover the index or clue that leads to the identification of the area on the game board where the jigsaw piece belongs. It is obvious that the complementary inscriptions on the jigsaw pieces and key cards are not restricted to any field of information, nor to being expressed by verbal text, but, especially in the case of young children, players may be in the form of related pictures of objects or events.

As a feature of especial attractiveness, and as an adjunctive aid to the putting together of the puzzle, the jigsaw puzzle in the aggregate may have an over-print of a picture, as shown at 10 in Figure 6, in addition to the inscriptions on the individual pieces.

A typical example of how the game may be played is described in the following rules.

If there is more than one player, the key cards are divided between them. For example, suppose that players "A" and "B" are playing the game: "A" selects the subject of "History," and "B" the subject of "Sports." Each of the players takes the card pertaining to the subject.

All of the jigsaw pieces are placed in the center of the board or on a table, and the players, by examining the inscription on each jigsaw piece, attempt to distribute the pieces between themselves in such a manner that each player will have before him only those jigsaw pieces which carry inscriptions relating to the subject matter of his card. For example, "A" picks up a jigsaw piece with the word "Chandler" upon it. "A" associates this inscription with baseball, and therefore, passes this jigsaw piece to "B" who has the subject "Sports." The next piece "A" picks up has the inscription "Jackson" upon it. He associates "Jackson" with "History," and since he himself has this subject, he will retain this jigsaw piece. This procedure is followed by the players until all of the jigsaw pieces have been classified and distributed to the players, with reference to the subject selected by each. In cases in which the player is uncertain as to how a jigsaw piece should be classified as to subject matter, he consults with the other player. After the pieces have been distributed, each player attempts to place each of the jigsaw pieces which has been distributed to him in its proper place on the game board. This is accomplished in the following manner.

"A" picks up one of his pieces on which the name "Jackson" appears. He associates "Jackson" with the subject of "History," so he refers to his card on the subject of "History." After examining the questions contained on his card, he concludes that "Jackson" is properly associated with item "Old Hickory" on his "History" card. Since the index adjacent "Old Hickory" is 27, "A" places this jigsaw piece on number 27 on the game board, which is its proper place if he has made a correct judgment with regard to the selection of the complementary inscriptions on the jigsaw piece and key card.

It will be found that if the jigsaw piece with the inscription "Jackson" is properly placed, it will interlock with adjacent jigsaw pieces. If it is not correctly placed, it will not interlock with the adjacent pieces, and the player should then review his judgment in associating the inscription on the piece with the inscription on the key card, consulting with his colleague, if necessary. The players may work together or alternately in building up this puzzle. The game calls for co-operation, forbearance and mutual assistance, rather than competition. It can, of course, be played by one person who assumes all of the key cards.

In the manufacture and sale of the game, it is contemplated that a single game board shall be standard for a plurality of different jigsaw puzzles with complementary key cards, so that when one has purchased the game, he may from time to time purchase additional different jigsaw puzzles with complementary key cards, the game to be played upon the same board. In this way the expense of purchasing a new board each time is avoided, while in due course the players will have acquired a wide fund of information upon various topics.

While I have in the above description disclosed what I believe to be a preferred and practical embodiment of the invention, it will be understood by those skilled in the art that the details of construction and arrangement of parts, as shown, are by way of example and not to be construed as limiting the scope of the invention.

What I claim as my invention is:

1. Game comprising a game board and a plu-

rality of game pieces designed to be aggregately arranged on said game board in a predetermined pattern, said game board having on its face distributively arranged indicia designating areas upon which respective game pieces belong but unrelated directly to any indicia embodied in the game pieces, each of said pieces bearing a different index unrelated to the indicia on the game board, means providing a list of items, each item comprising an index directly related to corresponding indicia on the game board and an index directly related to an index on the game piece, whereby a player determines where to place a game piece on the game board by matching the index on said piece with the directly related index of said item, thereby discovering in said item the index which relates directly to a corresponding index on said game board.

2. Game comprising a game board and a jigsaw puzzle including a plurality of jigsaw pieces designed to be put together upon said game board, said game board having on its face distributively arranged indicia designating areas upon which respective jigsaw pieces belong but unrelated directly to any indicia embodied in the game pieces, each of said pieces bearing a different index unrelated to the indicia on the game board, means providing a list of items, each item comprising an index directly related to corresponding indicia on the game board and an index directly related to an index on the jigsaw piece, whereby a player determines where to place a jigsaw piece on the game board by matching the index on said piece with the directly related index of said item, thereby discovering in said item the index which relates directly to a corresponding index on said game board.

3. Game comprising a game board and a jigsaw puzzle including a plurality of jigsaw pieces, designed to be put together on said game board, said game board having on its face distributively arranged indicia designating areas upon which respective jigsaw pieces belong but unrelated directly to any indicia embodied in the game pieces, said jigsaw pieces each having an inscription conveying an idea, unrelated to the indicia on the game board, means providing a list of items, said items each including an inscription conveying an idea and an index directly related to an index on said game board, the inscriptions of the several items being complementary to the inscriptions on the several jigsaw pieces, whereby a player determines where to place a jigsaw piece on the game board by matching the inscription on said piece with the complementary inscription of an item, thereby discovering in said item the index which directly relates to a corresponding index on said game board.

4. Game comprising a game board and a jigsaw puzzle including a plurality of jigsaw pieces, designed to be put together upon said game board, said game board having on its face distributively arranged indicia designating areas upon which respective jigsaw pieces belong but unrelated directly to any indicia embodied in the game pieces, said jigsaw pieces each having an inscription conveying an idea, unrelated to the indicia on the game board, the inscriptions on all the jigsaw pieces, with respect to the ideas conveyed being related to several subjects, key cards each devoted to one subject, providing a list of items under that subject, said items each including an inscription conveying an idea and an index directly related to one of the indicia on said game board, the inscriptions of the several items

being complementary to the inscriptions on the several jigsaw pieces, whereby a player determines where to place a jigsaw piece by referring it to the subject card relating to the same subject as the inscription on said piece, then matching the inscription on said piece with the complementary inscription of an item on said key card, thereby discovering in said item the index which directly relates to the corresponding index on said game board.
